[57] CLAIM

The ornamental design for a combination package of compressed fabric article and companion article, as shown.

DESCRIPTION

FIG. 1 is a perspective view of a combination package of compressed fabric article and companion article showing my new design, showing the top, front and one end; FIG. 2 is a rear side elevation view thereof;

FIG. 3 is a bottom plan view thereof;

FIG. 4 is an elevation view of the other end thereof; FIG. 5 is a perspective view of an alternate embodiment of FIG. 1, showing the top, front and one end;

FIG. 6 is a rear side elevation view of the package of FIG. 5;

FIG. 7 is a bottom plan view thereof; and,

FIG. 8 is an elevation view of the other end thereof.
